US0D1100445S

(12) **United States Design Patent** (10) **Patent No.:** **US D1,100,445 S**
(45) **Date of Patent:** **** Nov. 4, 2025**

(54) **FOOTWEAR**

(71) Applicant: **Crocs, Inc.**, Broomfield, CO (US)

(72) Inventor: **Salehe Bembury**, Los Angeles, CA (US)

(73) Assignee: **Crocs, Inc.**, Broomfield, CO (US)

(**) Term: **15 Years**

(21) Appl. No.: **29/956,723**

(22) Filed: **Aug. 8, 2024**

(51) LOC (15) Cl. **02-04**

(52) U.S. Cl.

USPC **D2/923**; D2/947; D2/952

(57) **CLAIM**

The ornamental design for footwear as shown and described.

DESCRIPTION

FIG. 1 is a front perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1–7 that are overlaid with a white transparent mask bounded by broken lines represent portions that form no part of the claimed design.

1 Claim, 7 Drawing Sheets
